ATTORNEYS

UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,541, dated September 19, 1899.

Application filed July 17, 1899. Serial No. 724,194. Term of patent 14 years.

To all whom it may concern:

Be it known that I, JEREMIAH A. SCRIVEN, a citizen of the United States, residing in the city, county, and State of New York, have 5 invented and produced a new and original Design for Bifurcated Nether Garments, of which the following is a specification.

The leading feature of my invention is a bifurcated nether garment, substantially as 10 shown in the accompanying drawing, the essential feature being the shape of the panel or insert thereof.

In the drawing the figure illustrates a rear 15 view of a bifurcated nether garment embodying my design.

In the drawing, A designates the body portion of a bifurcated nether garment having tubular members or extensions *a*, and B des-

ignates an insert or panel in the back of the garment. This insert has inner upright edges *b* extending along the tubular members and has outer substantially straight edges *c*, which join the curved edges *d*. The curved edges *d* extend from the tubular members inwardly and then outwardly toward the side of the 25 garment, where they join the curved edges *e*, that are curved in substantially opposite directions to the curved edges *d* and extend to the band *f* of the garment.

What I claim is—

The design for a bifurcated nether garment substantially as herein shown and described.

JEREMIAH A. SCRIVEN.
